REPRODUCTION OF SOUND

Glenn L. Dimmick, Haddonfield, N. J., assignor
to Radio Corporation of America, a corpora-
tion of Delaware

Application January 19, 1935, Serial No. 2,460

5 Claims. (Cl. 179—100.3)

This invention relates to the photographic recording and reproducing of sound, and has for its principal object the provision of an improved apparatus and method of operation whereby types 5 of sound records heretofore capable of being reproduced only in different types of devices may be reproduced by the same device.

In my copending application Serial No. 610,302 filed May 9, 1932, is disclosed a sound record on 10 which the positive and negative undulations are recorded on separate tracks spaced from one another so as to permit their images to be focused separately on different light responsive elements. As pointed out in the aforesaid application, this 15 spacing of the component parts of the record has the advantage that fogging between peaks at high frequency is avoided, background noise is eliminated, the tendency of an alternating current exciter lamp to produce hum in the reproduced sound is neutralized and the development of the 20 film is simplified.

A further object of this invention is to provide an apparatus operable to reproduce sound records irrespective of whether the positive and negative 25 undulations are recorded together or separately on tracks spaced apart from one another. In accordance with the invention, the light beam modulated by the sound-record is split into different components and these components are applied to the same or to different light sensitive elements depending on whether the negative and positive sound impulses are recorded on the same or different tracks or areas.

The invention will be better understood from 35 the following description when considered in connection with the accompanying drawing, and its scope will be pointed out by the appended claims.

The single figure of the drawing is a diagrammatic illustration of a sound reproducing apparatus embodying the invention.

This apparatus includes an exciter lamp 10 from which light of substantially constant intensity is applied to the sound record of a film 11 through an optical system 12. The sound record of the film 11 may be either the push-pull type of record disclosed by the aforesaid application or a record having all the sound components recorded on a single track. In either case the light beam acoustically modulated by the record of film or strip 11 is transmitted through

lenses and is split by lenses 14 and 15 into two separate beams one of which is applied to a stationary reflector 16 and the other of which is applied to an adjustable reflector 17.

With the reflectors 16 and 17 in their full-line 5 illustrated positions one of the acoustically modulated light beams is reflected by the stationary reflector 16 to the cathode 18 of a light sensitive device and the other light beam is reflected by the adjustable reflector 17 to the cathode 21 of the device 19. From the device 19, acoustically modulated current is supplied to a utilization apparatus such as a loud speaker, through means including an electrical source 22 connected to the lead of anode 23, a transformer 24, suitable 10 amplifiers (not shown) etc. Under these conditions, a record having its negative and positive impulses separately recorded on tracks spaced from one another is reproduced with all the advantages pointed out above.

When a record having all the sound components recorded on a single track is to be reproduced, the mirror 17 is shifted to the dotted line position and the two light beams are reflected to the cathode 18 and converted into corresponding electrical impulses in a manner too well understood to require further description. It will be apparent that any suitable type of electrical connection other than that illustrated may be utilized and that additional component light 20 beams may be controlled in the manner herein described.

I claim:

1. The combination of means for producing a plurality of acoustically modulated light beams, 35 a light sensitive device provided with a plurality of cathodes, means for directing selected portions of said beam, separate cathodes and means for selectively directing said portions to a single cathode.

2. The combination of means for producing a plurality of acoustically modulated light beams, 45 a light sensitive device provided with a plurality of cathodes, and means including a stationary reflector interposed in the path of one of said beams for directing said beam to one of said cathodes and an adjustable reflector interposed in the path of another of said beams for directing said beam to the same cathode or to a different cathode of said device.

40

50

3. The combination of means for directing a light beam through a sound record, means for directing selected portions of said beam to separate cathodes and means for selectively directing said portions to a single cathode.
4. In combination, means for directing a beam of light through a film sound track, means for dividing said beam into two portions, and means for alternatively directing said portions either onto two cathodes of a light sensitive device connected in a push pull circuit or onto only one cathode thereof, whereby either a push pull sound track or an ordinary sound track may be reproduced for the same apparatus.
- 10 5. In combination, means for directing a beam of light through a film sound track, means for dividing said beam into two portions, and means for alternatively directing said portions either onto two cathodes of a light sensitive device connected in a push pull circuit or onto only one cathode thereof, whereby either a push pull sound track or an ordinary sound track may be reproduced for the same apparatus.

GLENN L. DIMMICK.

CERTIFICATE OF CORRECTION.

Patent No. 2,097,758.

November 2, 1937.

GLENN L. DIMMICK.

It is hereby certified that error appears in the printed specification of the above numbered patent requiring correction as follows; Page 1, second column, line 38, after "beam" strike out the comma and insert instead the word to; and that the said Letters Patent should be read with this correction therein that the same may conform to the record of the case in the Patent Office.

Signed and sealed this 1st day of February, A. D. 1938.

Henry Van Arsdale,

(Seal)

Acting Commissioner of Patents.
